UNITED STATES PATENT OFFICE.

JOHN V. V. BOORAEM, OF BROOKLYN, NEW YORK.

APPARATUS FOR REVIVIFYING CHAR.

SPECIFICATION forming part of Letters Patent No. 584,071, dated June 8, 1897.

Application filed July 17, 1896. Serial No. 599,505. (No model.)

To all whom it may concern:

Be it known that I, JOHN V. V. BOORAEM, of the city of Brooklyn, in the county of Kings and State of New York, have invented a new and useful Improvement in Apparatus for Revivifying Char, of which the following is a specification.

In the apparatus heretofore commonly employed for the revivification of bone-black or, as it is commonly called, "char" for sugar refining and filtering purposes, the char after having been burned in retorts passes to coolers wherein by the act of cooling certain gases or vapors developed in it in the retorts and not expelled by the act of burning are condensed and caused to form tarry deposits, which to some extent close the pores of char and impair its filtering quality.

The object of this invention is to get rid of or dispel these gases or vapors between the retorts and the coolers; and the invention consists in the improvements hereinafter described and claimed for that purpose.

Figure 1 of the drawings represents a front view of as much of a revivifying apparatus as is necessary to illustrate my invention. Fig. 2 represents a transverse section taken in the line 2 2 of Fig. 1. Fig. 3 represents a vertical section taken in planes parallel with Fig. 1 on the line 3 3 of Fig. 2. Fig. 4 is an elevation taken at right angles to Fig. 1 of the mechanism for working what are herein-after termed the "regulators," which form an important feature of my invention. Fig. 5 represents a transverse section of the lower parts of the retorts and the upright parts of the cooling apparatus and intermediate devices, which constitute the principal elements of my invention.

Similar letters and numerals of reference designate corresponding parts in all the figures.

A designates the bottom plate, constituting the base of the kiln structure, having the tubes B, which constitute the calcining or revivifying retorts, seated in it in the usual or in any suitable manner, and being supported on a suitable number of columns C, only one of which is shown. The retorts are represented as arranged in rows, two of such rows being shown. Under each row of retorts B there is bolted to the plate A a box D, which may be

called the "receiving-box," and which runs under the whole row of retorts. This box D consists of a bottom, sides, and ends, and its top 55 is open to the retorts. In its ends there are hand-holes with covers 6 to allow for cleaning it out when necessary. It is preferably not closely jointed to the bottom plate, but is slightly open around its upper edges, as shown 60 in Figs. 2 and 5, for the vent of gases from its interior. The said box has in its bottom a series of openings a, one directly under each retort, the said openings being considerably contracted as compared with the retorts. On 65 one side of each of said openings is a slightly-downward projection b. Under each receiving-box D there is suspended by hangers E a rock-shaft F, which runs the whole length of the box and projects beyond one end thereof, 70 as shown in Figs. 1 and 3. This rock-shaft F carries a series of regulating devices or valves G, one for each retort, arranged under the respective openings a in the bottom of the box D for regulating the discharge of the char 75 from the said box. The said regulating devices are represented as valves, having the form of segments of cylinders, arranged with their faces at some distance below the openings a, but close or nearly so to the lower 80 edges of the projections b.

The cooling apparatus for two rows of retorts is represented as consisting principally of an upper box or trough H, a series of upright or nearly upright tubes I, and a series 85 of lower collecting-boxes J, all arranged on a sole-plate J*, said box or trough H and the series of tubes I and boxes J extending the whole length of the rows of retorts, the said box H, which is open at the top to the atmosphere, being at such distance below the plate 90 A that there is room for a free circulation of air between the retorts and cooling apparatus. The box or trough H is represented as suspended from the boxes D by the same hangers E which contain the bearings for the shaft F. The lower ends of the cooling-tube I are socketed into openings in the boxes J, and the said boxes, the sole-plate J*, common to all of the said boxes, and the tubes I are all represented as suspended through the sole-plate J* from the bottom plate A of the kiln structure by rods K. From the bottom of the box H a series of sockets c project downward for 100

the purpose of receiving and holding the upper ends of the cooling-tubes I, and in the interior of the bottom of the said box these sockets have funnel-like throats, as shown at 5 d d in Figs. 2, 3, and 5, the said throats debouching from the box with the funnel-mouths at the interior thereof, so that there are no flat surfaces left within the bottom for the lodgment of the char and that a continuous movement of the char from the box to the cooling-tubes is provided for.

At the bottom of each of the lower boxes of the cooling apparatus there is provided in the sole-plate J* an opening e, on one side of which is a downward projection f, and from the sole-plate J* there are suspended by hangers L two horizontal rock-shafts M, which extend the whole length of the rows of retorts and cooling-tubes and which carry a series of segment-valves N, one for each opening e. It may be here mentioned that these valves and their shafts are such as have been used at the bottoms of the coolers of revivifying apparatus for the purpose of regulating the discharge of the char from the coolers. The rock-shafts F are each provided with an arm F'; (see Figs. 1, 3, and 4,) and the rock-shafts M are each provided with an arm M', and the said arms are represented as connected with arms O', which are rigidly attached to a horizontal bar O, which is arranged transversely to the shafts F and M and which is fitted to slide lengthwise back and forth in guides g, attached to the columns C. The longitudinal movement of this bar may be produced by any suitable means, as by an eccentric P, as shown in Fig. 4, for the purpose of producing the oscillating movements of the valve rock-shafts F M, whereby the valves are caused to have to-and-fro movements. The connection between the arms O' of the bar O and the arms F' and M' of the valve rock-shafts should be such as to provide for varying the length of the to-and-fro movements of the valves, and for this purpose I have represented the said connections as consisting of gab-hooks h, pivoted to the said arms O' with provision for shifting the said gab-hooks from one to another of a series of studs i, arranged at different distances from the centers of the rock-shafts on their respective arms F' M'. By this provision for varying the to-and-fro movements of the valves G and N, I am enabled to properly regulate the delivery of the char from the retorts to the cooling apparatus and its discharge from the cooling apparatus.

Within or slightly above the open mouth of the box H there are arranged lengthwise of the box two screw conveyers Q, the shafts 60 of which have bearings at the ends of the box and are geared together in such manner as to rotate in opposite directions, the said screw conveyers being intended to give a slight movement to the upper portion of the char, which is deposited by the regulating-valves in a pile, as shown at j in Fig. 5, within the box H. Above the conveyers Q and parallel

with the shafts F are two air-pipes R, which are closed at one end and open at the other and which have numerous perforations k in their lower parts throughout their whole length. In the open ends of these air-pipes are introduced steam-injectors l for the purpose of introducing into the said pipes a current of air which, with the steam from the injectors, is caused to issue from the perforations k in small jets, which impinge upon the surface of the pile of char in the box H for the purpose hereinafter to be explained.

The operation is as follows: The boxes D 80 being kept freely supplied with char from the retorts B, on the regulating-valves G and N being set in motion a measured quantity of char is caused to be discharged from the boxes D through the openings a onto the valves G at 85 each movement of the said valves in the direction of the arrows shown upon them in Fig. 5. By the return movement of the said valves this char is pushed off them by the projections b on the bottom of the box and is 90 caused to fall through the air into the box H, on the bottom of which it forms a pile, as shown at j in Fig. 5, and whence it passes freely into the tubes of the cooling apparatus, from the bottom of which it is discharged 95 through the openings e by the movements of the regulating-valves N, operating in the same way as the regulating-valves G, as above described, the discharges through a and e being regulated to properly correspond with each other.

The hot char discharged from the boxes D contains some vapors or unfixed gases resulting from the decomposition in the retorts of organic matters which had been extracted 105 from the filtrate in the previous use of the char. In consequence of the loose or diffused condition in which it falls from the valve G into the box H these vapors or gases are liberated from the char, and owing to the glowing heat at which the discharge from the boxes D takes place a considerable proportion of such gases or vapors as are combustible will be consumed on exposure to the atmosphere, while such as are not combustible will 110 escape. Then as the char at a glowing heat is deposited layer upon layer in the pile j in the open box H the top layer is subject to still further exposure to the atmosphere, and a further combustion takes place by which all or nearly all of the unfixed gases or vapors, which would otherwise be recondensed and form tarry deposits in the char, are eliminated. The time of exposure of the char to the atmosphere, as hereinabove described, between 115 the retorts and the cooling apparatus is very short, as the top of the pile in the open box H is so quickly and repeatedly covered by the fresh deposits of the falling hot char, room being made for the fresh deposits by the withdrawal of the char from the bottom of the cooling apparatus.

Although by the combustion of the gases in the char during its fall through the at-

mosphere its temperature may be somewhat raised and the cooling process thereby postponed, the cooling will be commenced under cover from the atmosphere as soon as the 5 deposits in the box II are covered up by the succeeding deposits and will be so proceeded with in the box II and tubes I. The above operation is regulated so that the discharge 10 of the char from the boxes D may be in such measured quantities as are found to be most effectively operated upon by the air by adjusting the connections h between the arms F' of the valve rock-shaft, and those O' of the bar O to give a longer or shorter to-and-fro 15 movement of the regulating-valves G, according to the greater or less discharge required, a corresponding adjustment of the connections h between the said arms O' and the arms M' of the valve rock-shafts M being also 20 made when required.

The action of the air in producing the combustion of the gases or vapors in the falling char between the regulating-valves G and the box II and in the upper layer deposited on 25 the pile j of char in the said box is assisted by the jets of air from the pipes R, which pass through the falling particles and impinge upon the surface of said upper layer, and the combustion in said upper layer is 30 facilitated by the stirring action on said layers of the endless screw Q.

It may be here observed on reference to Fig. 5 that the downward projections b at the sides of the openings a in the bottom of each of 35 the two separate boxes provided for the two lines of retorts are on the right side of the said openings in the right-hand box and on the left side of the said openings in the left-hand box, and as the valves G of the two 40 boxes move in the same direction the said valves are caused to produce their discharges of the hot char alternately, so that the discharges from the two lines of retorts, though being deposited at or nearly at the same 45 point, are deposited one upon another in rapid succession, and the deposits are quickly covered from exposure to the air.

What I claim as my invention is—

1. In an apparatus for revivifying char, the 50 combination of two or more retorts arranged in a row, a receiving-box placed under and common to all of said retorts and having in its bottom contracted openings under said retorts, a cooling apparatus comprising an open 55 box located at such distance below said receiving-box as to provide for the free circulation of the air between them, and means for producing and regulating the discharge of the char through said contracted openings 60 from the receiving-box into the said open box, substantially as and for the purpose described.

2. In an apparatus for revivifying char, the 65 combination of retorts arranged in two parallel rows, receiving-boxes located one under each row of retorts in the row and having in its bottom contracted openings under its re-

spective retorts, a cooling apparatus comprising an open box located at such distance below said receiving-box as to provide for the 70 free circulation of air between them, two series of valves one series for each of said boxes to produce and regulate the discharge of the char from its contracted openings, and means of operating said two series of valves to produce alternate discharges of char from the two receiving-boxes into the said open box of the cooling apparatus, substantially as and for the purpose herein described.

3. In an apparatus for revivifying char, the 80 combination with retorts and a cooling apparatus so located below them as to provide for a free circulation of air under the said retorts and above the said cooling apparatus, of means of producing and regulating the discharge from said retorts to the said cooling apparatus and means for blowing air into the so-discharged char, substantially as herein described.

4. In an apparatus for revivifying char, the 90 combination with retorts and a cooling apparatus comprising an open box so located below them as to provide for a free circulation of air over said box, of means of producing and regulating the discharge of the hot char 95 from the retorts to the said box, and means of stirring the upper stratum of char in said box, substantially as herein described.

5. The combination with the receiving-boxes D and collecting-boxes J having openings a and e in their respective bottoms, the cooling-tubes I between the said boxes, the two rock-shafts F and M arranged respectively below the said boxes and carrying respectively valves, as G and N, for producing and 100 regulating the discharges through said openings, the sliding bar O and means of producing the longitudinal movement thereof, and variable connections between said bar and said rock-shafts whereby the movements of 105 the said valves relatively to each other may be produced and adjusted; all substantially as herein described.

6. The combination with the calcining-retorts arranged in rows, of the receiving-boxes 115 D one for each row of retorts having openings in their bottoms one for each retort for the discharge of the char received from the several retorts, the rock-shafts F one for each 120 row of retorts arranged under the said boxes and carrying valves G one for each of said openings for producing and regulating the discharge through said openings, the open box H located below the said receiving-boxes and common to both, and the hangers E dependent from said receiving-boxes and supporting both the said open box and the bearings for 125 said rock-shaft, substantially as herein described.

JOHN V. V. BOORAEM.
